BARBECUE GRILL TYPE COOKING APPARATUS

Walter Koziol, Russell, Ill., assignor to Charmglow
Manufacturing Co., Antioch, Ill., a corporation of Illinois

Filed Oct. 4, 1967, Ser. No. 8,861

Term of patent 14 years

Int. Cl. D7—04

U.S. Cl. D81—10

FIGURE 1 is a perspective view of a barbecue grill type cooking apparatus showing my design;

The dominant features of my design reside in the portions shown in full lines. The broken line showings of a support element in all of the figures and the handle in FIGURES 1, 2, 3, 5 and 7 are for illustrative purposes only.

What is claimed is:

The ornamental design of a barbecue grill type cooking apparatus, substantially as shown and described.
